UNITED STATES PATENT OFFICE

SHOJIRO ISHIBASHI, OF KURUME, FUKUOKA KEN, JAPAN

SHOE OR BOOT FOR LABORERS

Application filed May 5, 1928, Serial No. 275,526, and in Japan December 9, 1927.

This invention relates to shoes and has special reference to shoes having a rubber sole and cloth upper.

The principal object of the present invention is to provide a shoe having a cloth upper closed at its front by a medial seam running down over the instep of the shoe and protected at the bottom with novel means for reinforcing the seam at its lower part and for preventing leakage at the lower end of said seam.

With the above and other objects in view as will be hereinafter apparent, the invention consists in general of certain novel details of construction and combinations of parts hereinafter fully described, illustrated in the accompanying drawings and specifically claimed.

In the accompanying drawing the figure 20 is a perspective view of a shoe constructed in accordance with this invention.

In the invention as here shown the shoe is provided with an ordinary rubber sole 1 having a heel at its rear end. The upper consists 25 of two parts 3 and 3' of unequal size and these two side parts are united at their front edges by a medial seam 2 which runs down over the instep portion of the shoe from the top thereof. The part 3 terminates, as at 9, 30 rearwardly short of the medial heel line while the part 3' extends beyond this line as at 7 around the heel to overlap the rear of the part 3. Hooks 8 and loops 10 serve to connect these lapping parts and close the shoe 35 along this opening.

Just above the sole the upper is provided along its bottom edge with a rubber heel foxing 6 and a forward foxing 4 forming a comparatively narrow strip around the entire 40 lower edge of the upper. Covering the toe portion of the upper above this front foxing 4 is a lunate rubber reinforcing strip 5 having its lower edge engaging under the upper edge of the toe portion of the foxing 4 and its upper edge concavely curved. Above this strip 45 is a second rubber strip 5' having its lower edge formed to fit under the strip 5 and its end edges engaging under the upper edge of foxing 4 at opposite sides of the shoe. The 50 upper edge of this strip is curved concavely.

These two strips 5 and 5' cover the seam 2 at the toe and lower instep portions of the shoe thus reinforcing the front seam at these parts and effectually preventing the entrance of water through the lower part of this seam, 55 this being the part usually wet when walking on wet streets and roads.

There has thus been provided a simple and efficient device of the kind described and for the purpose specified.

Having thus described the invention, what is claimed as new, is:

A shoe having a rubber sole and heel and a cloth upper, said cloth upper consisting of two side portions joined at their front edges 65 by a medial seam running from the top down over the instep portion of the upper, a rubber foxing extending around the shoe immediately above the sole and heel and covering the lower edge of the upper, and rubber reinforcing strips extending across the lower part of said seam and covering the same above said foxing, one of said reinforcing strips being lunate in form and having its lower edge engaging under the upper edge of the forward part of the foxing and having its rear edge concavely curved, the other of said strips having its lower part formed to fit under the first strip and having its end edges engaging under the upper edge of said foxing at opposite sides of the shoe immediately behind the first strip.
